COMBINED ASH TRAY AND CIGARETTE
EXTINGUISHER OR SIMILAR ARTICLE

Frank E. Newkirk, Pacific Grove, Calif.

Application February 7, 1955, Serial No. 34,382

Term of patent 14 years

(Cl. D85—2)

FIG. 1

FIG. 2

FIG. 3

FIG. 5

Fig. 1 is a top plan view of a combined ash tray and cigarette extinguisher or similar article, showing my new design;

Fig. 2 is a front elevational view;

Fig. 3 is an end elevational view as seen from the right end of Fig. 2;

Fig. 4 is a bottom plan view; and

Fig. 5 is a top perspective view.

The broken line showing of cigarettes in Fig. 5 is for illustrative purposes only.

I claim:

The ornamental design for a combined ash tray and cigarette extinguisher or similar article, substantially as shown and described.
